UNITED STATES PATENT OFFICE.

THOMAS J. BENSON, OF MILO, OHIO.

DESIGN FOR A FRAME FOR LADIES' HATS.

SPECIFICATION forming part of Design No. 34,388, dated April 16, 1901.

Application filed March 11, 1901. Serial No. 50,760. Term of patent 3½ years.

To all whom it may concern:

Be it known that I, THOMAS J. BENSON, a citizen of the United States, residing at Milo, in the county of Franklin and State of Ohio, have invented and produced a new and original Design for Frames for Ladies' Hats, of which the following is a specification, reference being had to the accompanying drawing, forming part thereof, in which the figure 10 shows my newly-designed frame in perspective.

As shown in the drawing, the leading or material features of my design consist in forming the cup-like crown-frame with the right side thereof inclined, forming the rim with an upward flare from the base of the crown throughout the greater portion of said rim, providing said flaring rim portion with an inwardly-inclined and upwardly-extending roll-frame, which diminishes in height toward its ends, and connecting the ends of this inclined roll-frame with an upwardly and outwardly bowed smaller roll.

Of the parts described, *a* represents the 25 crown of the inverted-cup frame; *b*, the upright wires of one side thereof, which are inclined, and *b'* the substantially vertical side wires of said crown.

d represents the outwardly-extending and upwardly-inclined rim-wires, which radiate 30 from the base circle *c* of the crown and support the larger and front roll-frame *e*, the wires forming the latter being inclined inwardly, as shown.

f represents the smaller roll, which connects 35 the ends of the larger rolls, this smaller roll being located to the right of and adjacent to the rear side of the hat-frame. That portion of the rim which supports the smaller roll *f* is substantially horizontal, as shown. The front 40 and larger roll *e* is in its highest portions of greater height than the crown *a*.

Having described my invention, what I claim as new, and desire to secure by Letters Patent, is—

The design for a frame for ladies' hats as herein shown and described.

In testimony whereof I have signed my name to this specification in the presence of two subscribing witnesses.

THOMAS J. BENSON.
